H. T. BOWERSOCK,
AUTOMATIC RAILROAD SIGNAL.
APPLICATION FILED MAY 5, 1916.

1,250,784.

Patented Dec. 18, 1917.

UNITED STATES PATENT OFFICE.

HIRAM T. BOWERSOCK, OF LIMA, OHIO.

AUTOMATIC RAILROAD-SIGNAL.

1,250,784.

Specification of Letters Patent. Patented Dec. 18, 1917.

Application filed May 5, 1916. Serial No. 95,590.

To all whom it may concern:

Be it known that I, HIRAM T. BOWERSOCK, a citizen of the United States, residing at Lima, in the county of Allen and State of Ohio, have invented certain new and useful 5 Improvements in Automatic Railroad-Signals; and I do hereby declare the following to be a full, clear, and exact description of the invention, such as will enable others 10 skilled in the art to which it appertains to make and use the same.

This invention has for its object to provide an improved and efficient signal primarily designed for use in connection with railway 15 cars and adapted to be automatically actuated by track-carried means for automatically sounding the signal as the car approaches a crossing, switch or the like.

Another object is the provision of an automatic railway signal embodying a novel type 20 of trip-actuated valve for controlling the signal and also associated with the train pipe of the car to automatically open said train pipe and thereby cause the brakes of the car 25 to be automatically set.

With these and other objects in view, the invention consists in the novel construction, combination and arrangement of parts as will be hereinafter specifically described, 30 claimed and illustrated in the accompanying drawing, in which:

Figure 1 represents a fragmentary side elevation of a locomotive and track, illustrating the invention applied to use,

35 Fig. 2 represents a fragmentary longitudinal sectional view through the valve.

Referring to the drawing in detail, wherein similar reference numerals designate corresponding parts throughout the several 40 views, the numeral 5 indicates generally a well known type of locomotive adapted to travel upon a track 6 and equipped with the usual train pipe 7 for controlling the air brake system thereof.

45 In applying the invention to use, a vertically disposed valve case 8, preferably of cylindrical formation, is supported in the cab or other part of the locomotive and slidably receives a vertically movable cylindri- 50 cal valve 9, having a port 10 extending transversely therethrough. The opposite ends of the valve 9 are connected with longitudinally extending stems 11 and 12, the lower stem 12 being pivotally connected with 55 a shoe 13, which is pivotally secured at its rear end, as at 14, to a depending bracket 15

attached to the locomotive 5, and normally disposed above the track 6. The valve 9 is normally retained in downwardly extended position by the tension of a coil spring 16, 60 which is arranged in the valve casing intermediate the valve and an apertured partition 17.

A siren, or other type of signal 18, is supported upon the front of the locomotive 5 65 and is connected with an air or steam pipe 19, which extends rearwardly from the signal and connects with the lower portion of the valve casing 8 by a port 20. A second port 21 is formed in the valve casing diamet- 70 rically opposite the port 20 and is adapted to be connected therewith by the port 10 of the valve so as to connect the steam or air supply pipe 22 with the pipe 19 and thus conduct air to the signal 18 for operating the 75 latter. In its normal position, the valve 9 is so disposed as to obstruct the passage of air from the pipe 22 to the pipe 19.

The upper valve stem 11 is provided with two spaced and downwardly directed ratchet 80 teeth 23 adapted to coöperate with a spring actuated pawl or plunger 24 to lock the valve in its two positions. The pawl 24 is adapted to be actuated to release the valve and permit the latter to move to closed position under the influence of the spring 16, by 85 a pivoted lever 25 and a handle 26 connected therewith.

At a point above the ports 20 and 21 the valve casing 8 connects with the train pipe 90 7 controlling the air brake system of the car, and, when the valve is moved to its uppermost position, the port 10 thereof communi- 95 cates with the terminal of the train pipe 7 and permits the air to escape through the ex- haust pipe 27, thereby effecting a reduction 95 in the pressure of air in the train pipe and permitting the brakes to be automatically set.

The shoe 13 is adapted to be actuated to 100 move the valve 9 in position to register the port 10 with the ports 20 and 21 by a relatively stationary trip 28 fastened to the ties at a point in advance of a crossing, switch or the like. The valve is moved to its uppermost position so as to register the port 10 thereof with the terminal of the train pipe 7 and the exhaust pipe 27 by a resilient trip 29, which is preferably connected with an actuating mechanism (not shown) for automatically moving the shoe into and out of the path of the shoe 13. 110

In operation, when the pivoted shoe 13 engages the trip 28 it is moved upwardly, thereby lifting the valve 9 and moving the port 10 into registration with the ports 20 and 21 in the valve casing and permitting air to flow into and operate the signal 18. When thus actuated, the valve 9 is automatically locked in elevated position by the spring actuated pawl 24, which automatically swings inwardly and engages under the tooth 23. The valve may be subsequently released and closed by pulling outwardly upon the handle 26, swinging the lever 25 and withdrawing the pawl 24 from the tooth 23. The trip 29, when moved into the path of the pivoted shoe 13, effects an upward movement of said shoe and also of the valve 9, moving the port 10 thereof into registration with the inner open end of the train pipe 7 and permitting the air to escape through the exhaust pipe 27. It is obvious that the reduction of the air pressure in the train pipe will effect an automatic application of the brakes and thus stop the car or locomotive.

25 What I claim is:

A trip actuated signal for railways comprising the combination with a trip mecha-

nism, of a valve casing supported upon the locomotive and having a closed bottom and a partition arranged therein, a valve mounted in said casing intermediate said partition and bottom, a shoe pivotally connected at one end to said locomotive and pivotally connected at the opposite end with said valve, a fluid operated signal connected with and controlled by said valve, a spring arranged in said casing intermediate said valve and said partition to normally hold said valve in closed position, an upper and lower valve stem connected to said valve and extending respectively through the partition and bottom, outwardly projecting ratchet teeth formed on the upper valve stem, and means for engaging one of said ratchet teeth for automatically locking said valve in adjusted position, one of said ratchet teeth engaging the partition to limit the downward movement of said valve, as and for the purpose specified.

In testimony whereof I affix my signature in presence of two witnesses.

HIRAM T. BOWERSOCK.
